UNITED STATES PATENT OFFICE

137,298

DESIGN FOR A TELERAY SIGNALING DEVICE

William F. Sheffield, Baltimore, Md.

Application April 27, 1943, Serial No. 110,062

Term of patent 14 years

To all whom it may concern:

Be it known that I, William F. Sheffield, a citizen of the United States residing at Baltimore city and State of Maryland, have invented a new, original, and ornamental Design for Teleray Signaling Device, of which the following is a specification, reference being had to the accompanying drawing, forming part thereof.

Figure 1 as a plan view of a teleray signaling device, showing my new design,

Figure 2 is a front elevation of the device shown in Figure 1, and

Figure 3 is a side elevation of Figure 1.

I claim:

The ornamental design for a teleray signaling device, as shown.

WILLIAM F. SHEFFIELD.
